STOKER DISTRIBUTOR

John P. Cox, Evanston, Ill., assignor, by mesne assignments, to E. C. Ladenson, Evanston, Ill.

Application April 26, 1930, Serial No. 447,518

4 Claims. (Cl. 110—115)

This invention relates to stokers and more particularly to distributors therefor, although certain features thereof may be employed with equal advantage for other purposes.

5 It contemplates more especially the provisions of novel means capable of ready variation for effecting the uniform distribution of fuel over a grate of any configuration, design or area.

Stokers are now commonly employed for feeding fuel to grates, thereby relieving hand firing of furnaces in large or commercial installations. The success of stoker operation necessarily resides in effecting uniform fuel distribution within controllable consumption limits conducive 15 to maximum efficiency.

Grate areas and configuration vary considerably in different installations to meet particular requirements. For that reason, stoker distributors must effectively perform to accomplish uniform distribution thereover under varying requirements and grate areas. Then, too, the provision of an auxiliary air supply to the fuel during the delivery and over the grate thereof, is effective in improving stoker operation and combustion with increased efficiencies.

One object of the present invention is to simplify the construction and improve the operation of devices of the character mentioned.

Another object is to provide a rotary distributor 30 with blades of varying angles or inclinations.

Still another object is the provision of a rotor having a series of blades aligned thereon with varying angles of inclination determined by the distributing requirements.

35 A further object is to provide a rotor with circumferentially spaced series of blades thereon provided with varying angles of inclination to correspond with distribution requirements.

A still further object is to provide a rotor having circumferentially spaced alternate oppositely inclined series of blades thereon provided with varying angles of inclination conductive to particular requirements of distribution.

45 Still a further object is to provide a rotor with circumferentially spaced peripheral rods in parallelism with the axis thereof for pivotally receiving interchangeable blades of varying angles in series alignment.

50 Other objects and advantages will appear from the following description of an illustrative embodiment of the present invention.

In the drawings:

Figure 1 is a plan view in section of a furnace 55 grate together with a distributor in operative

association therewith to illustrate the teachings of the instant invention.

Figure 2 is a front view in elevation of a distributor embodying features of the present invention.

Figure 3 is a front view of a rotor constituting a part of the distributor shown in Figure 2.

Figure 4 is similar to Figure 2 with the distributor blades of somewhat different shape and directional inclination.

Figure 5 is a perspective view of an inclined blade with a left hand distributor direction.

Figure 6 is a perspective view of a similar blade having right hand distributor direction.

Figure 7 is a side sectional view showing a structure assembled with a furnace for fuel distribution with a distributor of the type shown in Figure 4.

The structure selected for illustration comprises a furnace 10 of any suitable construction which is provided with a boiler 11 thereabove in the usual and customary manner. A grate 12 is supported at the desired elevation within the furnace 10 rearwardly of the fire door 13. Draft doors 14 admit air into the ash pit 15 for circulation through the grate 12 to effect the combustion of the fuel deposited thereon. It must be appreciated that either a natural or forced draft system may be employed to meet the requirements of any particular installation, and for that reason the selected embodiment should be construed merely for illustration purposes rather than as a limitation.

A fuel feeder housing 16 is, in this instance, attached to the forward wall of the frame 10 in a position above the fire door 13 for directing fuel through a passage 17 for deposition upon the grate 12 in a manner which will appear more clearly hereinafter. A fuel hopper 18 is bolted or otherwise secured to the feeder housing 16 for communication therewith to confine fuel therein for gravity discharge to the housing 16 for distribution uniformly throughout the area of the grate 12. It is necessary or at least highly desirable that the fuel be distributed from the housing 16 over the grate 12 in a uniform layer for effective combustion over an extended period of time so that the heat generation will be substantially uniform and maximum, responsive to the greatest utilization of the B. t. u. therein conducive to high efficiency.

To accomplish this end, the distributor comprises a rotor 19 having the shaft extensions 20 thereof journaled in suitable bearings provided in the fuel feeding housing 16 which is shaped 110

proximate to the passage 17 to conform with the curvature of the rotor 19 so that fuel will be discharged to the grate 12 responsive to the operation thereof. As shown, the rotor 19 is provided with circular plates 21, in this instance three, spaced a short distance from the extremities and intermediate the length thereof to support circumferentially spaced rods 22, in this instance four. Intermediate discs 23 are disposed on the rotor 19 intermediate the rod spacer discs 21 to rigidify the structure and afford maximum bending resistance for support of distributor blades 24.

The blades 24 terminate in elongated hubs 25 which are provided with bores 26 extending axially therethrough for pivotal connection with the peripheral rods 22 of the rotor 19. As a result, any number of blades 24 may be arranged in successive series on the rods 22 for radial alignment thereon responsive to the influence of centrifugal force created in consequence of its rotation. Rotation of the rotor 19 may be effected at any desired speed owing to the operative connection of any suitable power source such as an electric motor (not shown). The fact that the blades 24 are mounted for free pivotal movement within a restricted circular range, renders them more or less yielding to obstructions such as hard substances in the coal so that the blades will pass thereover. After passing the obstruction, the centrifugal urge will cause the blades to assume the proper position with the other blades. This is very desirable in that fuel such as coal varies appreciably in size and for that reason a similar throw or displacement thereof toward the grate 12 responsive to the rotation of the distributor 19 will be effected.

It must be borne in mind that the grates 12 vary in size, shape and contour in different installations and types of furnaces. In consequence thereof, the distributor 19 must be readily adapted to meet different conditions and distribution requirements to insure the feeding of substantially uniform successive layers of fuel constituting in effect a more or less constant film upon the grate 12 during continued furnace operation to effect combustion with maximum efficiency. This is effected, in this instance, by providing blades 24 of varying angles of inclination so that the lanes of fuel distribution will be in fan formation (indicated by lines 27—Figure 1) over the entire grate area 12.

So that the entire area of the grate 12 may receive fuel in substantially equal increments to define a uniform film thereover, it has been found desirable that alternate rods 22 be provided with the blades having left and right hand inclination of varying angularity from one extreme edge to another. With the structure herein described a series of four rods 22 provides an equal number of alternate right and left hand series of adjacent blades 24, thereby directing the fuel in lanes of fan formation to both the sides and center of the grate 12 to cover substantially the entire area thereof with a uniform fuel film of a thickness conducive to maximum efficiency for any particular installation. The quantity of fuel and thickness of the fuel film upon the grate 12 is controllable by the rotary speed of the distributor 19 and linear extent or frequency of reciprocation of a pusher box 28 constituting the feeding member mounted in the housing 16 for operation in a manner more particularly disclosed and described in the patent to Cotton numbered

The difference in inclination and variation of distributor blades 24 together with their respective positions along the rods 22, depends largely upon the requirements of any particular installation including the grate areas thereof, this varying within a wide range in that standard grate areas are uncommon and not altogether possible. Specific blade series and angularity variations found especially effective for certain grate areas and dimensions are illustrated as follows:

Blade angularity in degrees

Rod series	For grates 5'-0" wide x 5'-0" deep									90
	1 R. H.	30	30	35	35	40	40	45	45

4 L. H.	50	45	40	35	RH	35	30	35	45	50

Furthermore, to meet certain requirements for fuel distribution in increased quantities on one side of the grate compared with the other, a series of blades on a single rod may be divided into right and left hand as illustrated in the following specific instances which have proven successful for their intended purpose.

Blade angularity in degrees

Rod series	For grates 3'-6" wide x 4'-0" deep									130
	1 R. H.	30	30	35	35	40	40	45	45

For grates 6'-0" wide x 4'-0" deep										
1 L. H.	50	45	40	40	35	RH	35	30	30	145
2 L. H.	50	45	40	35	RH	35	30	45	45	50
3 R. H.	30	30	35	35	40	RH	30	45	50	50
4 L. H.	50	45	40	35	RH	35	40	45	50	50

It is obvious from the above specific applica- 150

tions of blade series with angularity variations that the number of blades in the series as well as the particular spacing thereof is capable of wide modification to meet any particular conditions and operating requirements. The fact that the blades 24 have their hubs 25 pivotally connected to the sustaining rods 22, renders such variations very simple without entailing much labor or expense. Moreover, such may be accomplished during the assembly or installation of the structure, and any unforeseen operating requirements may be provided for with an arrangement such as described hereinbefore. The blades preferably have lateral projections 29 extending beyond the hub 25 to overlap the adjacent blades 24 on both sides thereof to preclude the passage of fuel therebetween.

To this end, the lateral extensions 29 thereof are provided with grooves 31 for a predetermined extent along the side edges thereof in communication therewith to define shoulders 32. The grooves 31 are on the forward blade surface thereof complementary to the edge of the adjacent blades, thereby affording the reception thereof for continuous alignment defining a fuel distributor surface. In order to promote more complete combustion, secondary air tuyères constituting perforated metallic blades 33 are provided forwardly of the grate 12 proximate to the fire door 13 to establish communication between the ash pit 15 and the combustion space. In consequence thereof, air is admitted above the fuel bend and over the grate 12 to effect more complete commingling of air with the combustion vapors as well as to impart aeration to the fuel during its passage from the distributor 19 to the grate 12 through the opening 17. This is conducive to more complete combustion of the fuel thereby enabling increased thermal efficiency.

I claim:

1. A fuel distributor comprising a rotor having a plurality of circumferentially spaced shafts, said shafts each having a series of fuel distributing blades thereon, the pitch of said blades of certain series varying in selected degrees along said shaft, the blades being arranged in groups of opposite pitch and so constructed as to effect uniform expansive fuel distribution. 80

2. A fuel distributor comprising a rotor having a plurality of circumferentially spaced shafts, said shafts each having a series of fuel distributing blades thereon, the pitch of said blades of certain series from a point intermediate the series being opposed and varying in selective increments towards the ends of the shaft to effect uniform expansive fuel distribution. 85

3. A fuel distributor comprising a rotor having a plurality of circumferentially spaced shafts, said shafts each having a series of fuel distributing blades thereon, each of said series comprising groups of blades of uniform pitch, the pitch of sequential groups along said shaft varying in selected increments from one end thereof, certain common shaft series of blades on said 100 rotor having opposite pitch to effect uniform expansive fuel distribution. 95

4. A fuel distributor comprising a rotor having a plurality of circumferentially spaced shafts, said shafts each having a series of fuel distributing blades thereon, said series comprising groups of blades formed so that their bases and outer edges lie at an angle with respect to each other, the pitch of a certain shaft series of blades increasing from one end of the shaft to the other, 110 the adjacent circumferentially spaced shaft having a common blade series of opposite pitch to effect uniform expansive fuel distribution. 110
